US00D616932S

(12) **United States Design Patent**
Albers et al.

(10) **Patent No.:** US D616,932 S
(45) **Date of Patent:** ** Jun. 1, 2010

(54) **TRANSACTION CARD**

(75) Inventors: **Chad Albers**, Minneapolis, MN (US);
Ted C. Halbur, Lino Lakes, MN (US);
Adam W. Reynolds, Minneapolis, MN (US); **David K. Sheldon**, Loveland, OH (US)

(73) Assignee: **Target Brands, Inc.**, Minneapolis, MN (US)

(**) Term: **14 Years**

(21) Appl. No.: **29/352,744**

(22) Filed: **Dec. 24, 2009**

(51) **LOC (9) Cl.** 19-08

(52) **U.S. Cl.** D19/9

(58) **Field of Classification Search** D19/1-34, D19/39, 40; 40/124.01-124.15, 672, 661, 40/726, 776, 617; 283/72, 74, 75, 103, 105, 283/106; 235/380; 206/449; D21/385, 588; D20/10, 22, 27, 40, 42, 11; D14/435-437; D25/141, 149, 156; 273/452; D10/64; 33/562; D7/557

CLAIM

The ornamental design for a transaction card, as shown and described.

DESCRIPTION

FIG. 1 is a front, perspective view of a transaction card showing an embodiment of our new design;

FIG. 2 is a front view thereof;

FIG. 3 is a rear view thereof;

FIG. 4 is a top view thereof, the bottom view being a mirror image of the top view; and,

FIG. 5 is a right side view thereof, the left side view being a mirror image of the right side view.

The features shown in broken lines depict environmental or other associated subject matter and form no part of the claimed design.

1 Claim, 3 Drawing Sheets
